We claim the ornamental design for a chip for biochemical examination, as shown and described.

DESCRIPTION

FIG. 1 is a front perspective view of a chip for biochemical examination of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-section view taken along the line 9-9'-9" of FIG. 4 with the internal parts being omitted;

FIG. 10 is a cross-section view taken along the line 10-10 of FIG. 4 with the internal parts being omitted;

FIG. 11 is a cross-section view taken along the line 11-11 of FIG. 4 with the internal parts being omitted; and,

FIG. 12 is a cross-section view taken along the line 12-12 of FIG. 4 with the internal parts being omitted.

The broken lines shown represent unclaimed subject matter and form no part of the claimed design. Additionally, the unevenly broken lines in the drawings define the limits of the claimed design.
